UNITED STATES PATENT OFFICE.

CHRISTOPHER E. HERTLEIN, OF NEW YORK, N. Y.

DESIGN FOR A SKIRT-PROTECTOR.

SPECIFICATION forming part of Design No. 33,404, dated October 16, 1900.

Application filed August 10, 1900. Serial No. 26,532. Term of patent 14 years.

To all whom it may concern:

Be it known that I, CHRISTOPHER E. HERTLEIN, a citizen of the United States, residing at New York, borough of Manhattan, and 5 State of New York, have invented and produced a new and original Design for Skirt-Protectors, of which the following is a specification, reference being had to the accompanying drawing, which represents a portion o in side elevation.

The leading or material features of my design are individual spaced tassel-shaped portions at the lower edge, a series of short parallel ribs extending longitudinally and arranged 5 at the inner end of each of the tassel-shaped portions, and short transverse ribs between the various series of short parallel ribs.

a indicates the tassel-shaped portions, b the several series of short parallel ribs, and c the short intermediate transverse ribs. The tassel-shaped portions a flare downwardly and are separated by pointed spaces a' below the ribs c. Above the ribbed portions is a broad longitudinal portion d. 20

What I claim is—

The design for a skirt-protector, as shown and described.

In testimony that I claim the foregoing as my invention I have signed my name in presence of two subscribing witnesses.

CHRISTOPHER E. HERTLEIN. 25
